UNITED STATES PATENT OFFICE.

FREDERICK E. KOHLER, OF CANTON, OHIO.

TREE-PROTECTOR.

SPECIFICATION forming part of Letters Patent No. 338,158, dated March 16, 1886.

Application filed September 5, 1885. Serial No. 176,251. (No model.)

To all whom it may concern:

Be it known that I, FREDERICK E. KOHLER, a citizen of the United States, and a resident of Canton, county of Stark, State of Ohio, have 5 invented a new and useful Improvement in Tree-Protectors, of which the following is a full, clear, and exact description, reference being had to the accompanying drawings, making part of this specification.

10 My invention relates to improvements in tree-protectors; and it consists in means that will protect the tree from violence, and at the same time allow the air to circulate freely about the tree, that is portable, and may be 15 knocked down and packed in nests for convenience of storing or shipping.

With these objects in view my invention consists in certain features of construction and combination of parts herein specified and set 20 forth in the claims.

Figure 1 is an elevation of my improved tree box or protector, showing the manner of applying it to a tree. Fig. 2 is a sectional view showing the manner of dividing the protector. In this view one half of the hoop is seen and three-eighths of the number of slats and one of the three anchoring-stakes. Fig. 25 3 is also a sectional view of the remaining half of the hoops and five-eighths of the slats and 30 the remainder of the anchoring-stakes. Fig. 4 is a view of the protector when knocked down and "nested" for shipping. Fig. 5 is a view of the hoop, showing the depressions or sockets formed to receive the slats, also showing a 35 difference in the diameters of the two sections.

A represents the slat used in forming the tree-protector, which may be made of any desired length and width, preferably about six feet long and one and three-fourths of an inch 40 wide; B, the hoop, which may be formed of iron or steel of a width and thickness adapted to circumstances, preferably from one inch to one and one-half inch in width and from one-eighth to three-sixteenths in thickness. 45 It is formed in two parts, semicircular in form, as shown in Fig. 5, and having depressions *a* formed on their inner surface to receive and support the slats. The ends of the semicircular parts that form the hoop may be drawn 50 down into the form of a wedge and lap one on

the other, so as to form a joint of about the same thickness as the metal of the hoop.

Preferably I use in the construction of my improved tree-protector eight slats and three hoops. The slats are placed in the depressions and bolted or riveted in position, as shown in Fig. 2. The three slats of one section are permanently fixed to the three half-hoops, leaving the ends *b* of the half-hoops free to lap over the ends *b'* of the hoops of the other section on which the other slats are placed. A bolt is then passed through and securely unites the ends of the hoops and the two opposite slats, and thus forms an annular protector or fence about the tree, as seen in 65 Fig. 1.

To keep the protector in position the anchor-stakes C are provided. These may be attached to the protector by one of the bolts, which is of sufficient length to pass through the stake, 70 hoop, and slat, and firmly secure them together.

The joining of the halves together by the same set of bolts that secure the two opposite slats also further reduces the initial cost, as 75 well as provides a tree-protector more easily handled and placed in position.

My method of placing the protector is to bolt the two parts together about the tree, with one end resting on the ground, so that the 80 tree may be central thereto and mark the place that the stake should be driven, move the protector to one side and drive the stake to the desired depth, and so on until the three stakes are driven.

If desired, the stakes may be secured to the protector before the latter is secured around the tree, so as to bring the protector into the desired position, whether it be vertical or inclined, so as to adapt it to the tree.

I would call especial attention to the manner of nesting the protectors when not in use, or for convenience in handling and shipping, one half of each hoop being so formed as to drop inside of the other—in other words, forming the hoop in two sections of different diameters, section B' a little smaller than section B, so as to allow the smaller to rest inside of the larger; and yet the diameter of the two parts are so near the same that when bolted 95 100

together in the form of a tree-protector they will appear to be formed of one circle or diameter.

I am aware that it is not broadly new to 5 construct a tree-protector of two parts of unequal size, and am also aware that in wire fences it is not new to form depressions in the wire for the reception of the pales.

In my device the two sections of the bands 10 are practically the same length, and the parts, when knocked down for shipment, rest snugly one within the other.

Having thus fully described the nature and 15 object of my invention, what I claim, and desire to secure by Letters Patent, is—

1. A tree-protector made of two parts of 20 different diameters, each part consisting, essentially, of semicircular bands or hoops having depressions therein, and a series of slats separated, as shown, and secured within the depressions in the semicircular bands or hoops, the two parts being united by overlapping and

securing together the ends of the bands, substantially as set forth.

2. In a tree-protector, a supporting hoop 25 formed in two sections semicircular in form, of different diameters, and having depressions formed therein for a lateral support for the slats, substantially as described and set forth.

3. A tree-protector made in two parts of 30 different diameters, each part consisting, essentially, of semicircular bands or hoops having depressions formed therein, slats secured within the depressions in the bands or hoops, and the stakes C, all of the above parts combined substantially as set forth.

In testimony whereof I have hereunto set my hand this 3d day of September, A. D. 1885.

FREDERICK E. KOHLER.
